(57) **CLAIM**

The ornamental design for an electronic thermometer with wireless communication device, as shown and described.

DESCRIPTION

FIG. 1 is a front, top, and left side perspective view of an electronic thermometer with wireless communication device, showing our new design;

FIG. 2 is a rear, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is an enlarged view of the circumscribed area IX in FIG. 1; and,

FIG. 10 is a front, top, and left side perspective view of the left portion thereof, shown at an enlarged scale.

The dashed broken lines in the figures illustrate portions of the electronic thermometer with wireless communication device that form no part of the claimed design. The dot-dot-dashed broken lines in FIGS. 1 and 9 circumscribe the enlarged views and form no part of the claimed design.
